ABSTRACT OF THE DISCLOSURE

Alkali perborates and percarbonates are spray dried by a process wherein the spray charge contains only the stable base components and the active oxygen carrier is directly led into the spray charge before the atomization and the mixture is then sprayed and dried in a spray tower.

The present invention is concerned with a process for the production of alkali perborates and percarbonates by spray drying processes. The alkali perborates and percarbonates (also called alkali peroxoborates and alkali carbonate peroxohydrates) are extensively used for the production of powdered washing, bleaching and purifying agents.

For the production of powdered washing, bleaching and purifying agents spray drying processes are employed predominantly. In these processes a spray charge consisting of an aqueous solution of the active washing agent, washing assistant agent and additives is atomized through a spray device in a tower. Hot air is injected into the spray tower in order to remove excess water. There is obtained a dry, voluminous powder, the so-called spray product. Since the active oxygen containing compounds such as alkali perborates and percarbonates necessary as the bleaching constituents are inclined to be destroyed by the action of elevated temperatures and the presence of certain other chemicals these bleaching agents are generally added subsequent to the spray product.

The usual method for the production of alkali perborates or percarbonates consists of reacting the alkali borate or carbonate with hydrogen peroxide in aqueous solution whereby the active oxygen containing compounds precipitate as a crystalline product. They are separated off and carefully dried.

It is detrimental to the mixing of the spray product and the active oxygen containing compounds that the individual particles of both components are very different in form and density on account of their different methods of production as a result of which it is difficult to obtain homogenous mixtures.

To eliminate this advantage of different granular structure between the washing agent-spray product and the bleaching agent it was attempted to likewise prepare the perborate and percarbonate by spray drying processes.

However, great difficulties were encountered. On account of the relatively difficult solubility of alkali perborate or percarbonate in a spray charge it is necessary to operate with very dilute solutions, about 2-4 weight percent aqueous solutions. If the temperature of the spray charge is raised in order to increase the solubility a destruction of the active oxygen already occurs in the solution being sprayed. This leads to active oxygen loss and to irregularity in the spraying process.

It has now been found that alkali perborates or percarbonates can be produced in spraying drying processes if the spray charge only contains the stable base compo-

2

nents of the per compounds and the active oxygen carrier is introduced into the stable components immediately before (usually 1 inch to 10 inch) the atomization whereupon the mixture is sprayed at customary temperatures in the spray tower and is dried there in conventional manner.

As alkali perborates and percarbonates there can be prepared for example sodium perborate, potassium perborate, sodium percarbonate and potassium percarbonate.

The stable base components are present as aqueous solutions in concentrations of 20 to 100 weight percent, in other words, the base components are capable of addition as aqueous or water free melts.

Unless otherwise indicated, all parts and percentages are by weight.

The active oxygen carrier, of which hydrogen peroxide is most important are generally added in aqueous solutions of 25 to 70 weight percent although the concentration can range from 5 to 95%. In place of hydrogen peroxide, there can be used alkali peroxides, as sodium peroxide. These solutions can be made stable by the addition of alkali or alkaline earth silicates or phosphates, e.g., sodium silicate, potassium silicate, sodium meta silicate, calcium silicate, sodium pyrophosphate, potassium pyrophosphate, sodium ortho phosphate, potassium ortho phosphate or alkaline earth halides, e.g., magnesium chloride.

As "base components" there can be employed alkali borates and carbonates, e.g., sodium metaborate, borax, potassium metaborate, potassium tetraborate, sodium carbonate, potassium carbonate, sodium bicarbonate and potassium bicarbonate. The base components can be added as such or in the form of alkali hydroxides, e.g., sodium hydroxide or potassium hydroxide and borax or carbon dioxide or boric acid.

The atomization is carried out with conventional nozzles, preferably with compressed air atomization, above all if the materials to be sprayed are not highly fluid (see, for example, Ullmann, Enzyklopädie der Technischen Chemie, vol. 1, page 603 and page 729 ff.).

The temperature of the drying air is 60-200° C., that of the exit air which corresponds to about that of the sprayed product to about 40-100° C.

It is also possible to use for the spray charge not the entire base components but only a partial component, i.e., either only the alkali portion or only the acid residue as the borate or carbonate components, as an additive to the spray charge and afterwards mix the second component with the active oxygen carrier.

The technical advance of the process of the invention lies in the possibility of spraying alkali perborate or percarbonate without increased loss of active oxygen occurring as is the case with the customary crystallization process. The loss is 5 to 8%. The per compounds accumulate furthermore in such particle size that they can be homogeneously mixed with other washing agent constituents without difficulty.

The process is especially suited for the production of products containing small quantities of water of crystallization with correspondingly high active oxygen contents.

By dilution with inorganic salts which are added in the spray charge, it is possible to make up lower active oxygen content products. Examples of such inorganic salts are sodium sulfate, potassium sulfate, sodium carbonate, potassium carbonate, sodium orthophosphate, potassium orthophosphate. When such inert salts are added they can be used in an amount of 2 to 80% of the total composition.

The process of invention will be best understood in connection with the drawing and following examples.

The single figure of the drawing is a schematic diagram of an apparatus suitable for use according to the invention.

Referring more specifically to the drawing, there is provided an atomizer 1 into which are introduced the active oxygen carrier over liquid conduit 2, spray charge through conduit 3 and compressed air through conduit 4. In zone 5, the reaction occurs, the mist goes out from the atomization zone 6 into the drying chamber (not shown) and is dried in known manner.

EXAMPLE 1

In order to produce a spray charge 134.3 parts by weight of sodium metaborate (NaBO_2) was dissolved with heating to 40° C. in 289.7 parts by weight of water. This solution was sprayed into an atomization drier over a period of 45 minutes. Shortly before the spray nozzle (about 6 inch) to the spray charge, there was homogeneously added 292 parts of hydrogen peroxide (23.7 weight percent in water), which contained 0.4% magnesium chloride (MgCl_2). The temperature of the drying air amounted to 98° C. at the entrance to the tower and to 50° C. at the exit. There was obtained 206 grams of sodium perborate with an active oxygen content of 15.04% which corresponds to a yield based on the active oxygen of 95%.

EXAMPLE 2

To produce a spray charge 252 parts by weight of sodium metaborate (NaBO_2) and 137 parts by weight of sodium sulfate (Na_2SO_4) were dissolved in 1036 parts by weight of water with heating to 40° C. This solution was processed in the course of an hour in an atomization drier while there was added homogeneously to the liquid stream shortly (6 inch) before the spray nozzle 282 parts by weight of hydrogen peroxide (49 weight percent) which contained 0.5% magnesium chloride. The temperature of the drying air at the entrance to the tower was 163° C. and at the exit 93° C. There was obtained 544 grams of sodium perborate with an active oxygen content of 11.00%, corresponding to an active oxygen yield of 92%.

EXAMPLE 3

1094 parts by weight of potassium metaborate (KBO_2) were dissolved in 1734 parts by weight of water and cooled to 20° C. to form a spray charge. The solution was sprayed into an atomization drier in the course of 195 minutes. Shortly (6 inch) before the spray nozzle 2660 parts by weight of hydrogen peroxide (34.4 weight percent) containing 0.5% magnesium chloride (MgCl_2) were homogeneously added. The temperature of the drying air at the entrance to the tower amounted to 103° C. and at the exit to 71° C. There were obtained 2030 grams of potassium perborate with an active oxygen content of 20.11%, corresponding to an active oxygen yield of 95%.

EXAMPLE 4

261.3 parts by weight of sodium carbonate (Na_2CO_3), 42.7 parts by weight of sodium bicarbonate (NaHCO_3) and 1.2 parts by weight of sodium pyrophosphate ($\text{Na}_2\text{P}_4\text{O}_7$) were dissolved in 1188.8 parts of water with heating and then cooled to 18° C. to form a spray charge.

5 This solution was added to a spray tower in the course of 68 minutes while shortly (6 inch) before the spray nozzle as homogeneously as possible there were added 322 parts by weight of hydrogen peroxide (34 weight percent) which contained 0.5% magnesium chloride. The temperature of the drying air amounted to 73° C. at the entrance and to 46° C. at the exit. The product obtained (412 g.) had an active oxygen content of 11.95% which amounted to a yield of 95% based on the active oxygen.

EXAMPLE 5

10 As a spray charge 18.3 parts by weight of sodium hydroxide (NaOH) were dissolved in 91.5 parts by weight of water. This solution was sprayed into an atomization drier in the course of 65 minutes. Shortly (6 inch) before the spray nozzle, there were homogeneously added 87.2 parts by weight of borax ($\text{Na}_2\text{B}_4\text{O}_7 \cdot 10\text{H}_2\text{O}$) dissolved in 92.3 parts by weight of hydrogen peroxide (35 weight percent). The temperature of the drying air amounted to 90° C. at the entrance to the tower and to 48° C. at the exit. There were obtained 101 grams of sodium perborate with an active oxygen content of 14.5% corresponding to an active oxygen yield of 96%.

15 What is claimed is:

- 20 1. A process for spray drying alkali perborate or alkali percarbonate comprising employing as a spray charge the stable base component and adding the active oxygen carrier immediately before the atomization of the spray charge in the spray tower and thereafter drying the mixture.
- 25 2. A process according to claim 1 wherein hydrogen peroxide is the active oxygen carrier.
- 30 3. A process according to claim 1 wherein the spray charge contains only the acid or the alkali component of the borate or carbonate and the other of the alkali or acid component is added with the active oxygen carrier.
- 35 4. A process according to claim 3 wherein the active oxygen carrier is hydrogen peroxide.
- 40 5. A process according to claim 1 wherein the base component contains alkali metal borate or carbonate.
- 45 6. A process according to claim 1 wherein the spray charge is in the form of an aqueous solution having a concentration of 20 to 100%.
- 50 7. A process according to claim 6 wherein the active oxygen carrier is hydrogen peroxide and the drying temperature is 60 to 200° C.
- 55 8. A process according to claim 1 wherein an inert salt is included in the components to be sprayed.
